UNITED STATES PATENT OFFICE

GEORGE H. JUNG, JR., OF CINCINNATI, OHIO, ASSIGNOR TO THE JUNG ARCH BRACE COMPANY, OF CINCINNATI, OHIO, A CORPORATION OF OHIO

ARCH BRACE STRUCTURE

Application filed July 23, 1928. Serial No. 294,690.

This invention relates to an arch brace structure of the arch cuff type and has for an object the provision of a simplified pad receiving pocket.

5 Another object is to provide a structure of this kind wherein a pad receiving pocket is joined at one of its lateral edges so that the pad may be inserted in adjusted positions therein, either above or below the band.

10 These and other objects are attained by the means described herein and disclosed in the accompanying drawings, in which:

Fig. 1 is an inverted plan view of a device of the invention.

15 Fig. 2 is a cross sectional view taken on line 2—2 of Fig. 1.

Fig. 3 is a view taken on line 3—3 of Fig. 1.

20 Fig. 4 is a perspective view of an adjustable pad for insertion in the pocket of the device.

Heretofore it was customary to make cuff type arch supports of the pad holding type with a pocket member closed at the front and back and open at both sides. An elastic 25 cuff extended between the pocket forming members and was stitched transversely of its width to the inner face of the bottom pocket forming member. The pad was loosely inserted between the elastic cuff and the top pocket forming member.

30 In the present invention the pocket is formed of a top member 6 and a bottom member 7, preferably of leather, between which extends the usual endless elastic cuff 8. The 35 pocket members are secured together at the front and rear by stitching 9 and 10. A single row of stitching 12 secures both the top and bottom members to the cuff 8 and precludes shifting of the pocket thereon. 40 Thus there are two pad receiving pockets 13 and 14, one on each side of the cuff. When the wearer has very tender feet, it is very advantageous to place the soft resilient pad 15 in the desired position in pocket 14 so as 45 to dispose both the cuff and top member 6 between the foot and the pad. Ordinarily the pad 15 would be placed in pocket 13 as shown.

The pockets 13 and 14, it will be noted, open 50 only on the lateral side 16 which is preferably

disposed at the inside of the foot, thereby permitting of a greater adjustability for the pad under that portion of the arch where it is most often needed.

The simplified structure is also easier to 55 manufacture because it does not require that the pocket structure be turned inside out while attaching it to the cuff.

What is claimed is:

50 In a device of the class described the combination of a pair of similar pocket forming members secured together at the front, rear and one side and an elastic cuff extending between said members and secured to both of them at the said side of the members.

55 In testimony whereof, I have hereunto subscribed my name this 18th day of July, 1928.

GEORGE H. JUNG, JR.
